R. E. DILL

CISTERN

Filed March 12, 1923

RICHARD E. DILL INVENTOR.

BY
Emil F. Lange ATTORNEY

UNITED STATES PATENT OFFICE.

RICHARD E. DILL, OF ALEXANDRIA, NEBRASKA.

CISTERNS.

Application filed March 12, 1923. Serial No. 624,449.

To all whom it may concern:

Be it known that I, RICHARD E. DILL, a citizen of the United States, residing at Alexandria, in the county of Thayer and State of Nebraska, have invented certain new and useful Improvements in Cisterns, of which the following is a specification.

My invention relates to cisterns, and it has particular reference to a cistern which is specially adapted for use on farms and suburban places to furnish a constant supply of water for the home and for the barn-yard.

Certain conditions affecting water supply systems are common to a large portion of the entire Mississippi Valley, and these conditions must be considered in designing a successful system of this kind. Nearly all farms and suburban homes in the middle west include one or more windmills as a part of their equipment. While the farm is largely dependent on the windmill for the power for raising the water, this power fluctuates and frequently does not function for short periods with the result that the owner must pump the water by hand or must use an engine until the wind blows again. This condition has resulted in the installation of many pressure tanks of various kinds, probably the most popular of which has been the steel tank.

The steel tank has not been altogether satisfactory owing to its high initial cost, its short life, and its tendency to rust and to thus taint the water. It has long been recognized that the underground pressure cistern made of concrete would be the ideal cistern, but the high cost of cast concrete and the tendency of the concrete to check and crack and to thus release the pressure have combined to discourage the use of concrete for this purpose.

A climatological factor of the middle west which affects the success of the underground cistern is the range of temperatures between wide extremes. Such temperatures may vary in a single year between forty degrees below zero to a hundred and ten degrees above. During periods of extreme heat the water in storage may be so warm as to be unfit for drinking purposes, but when the opposite extreme is reached the system is apt to cease functioning or even to burst because of the freezing of the water. In the ideal system the water would of course have

a fairly constant temperature regardless of variations in the outside temperatures.

Among the objects of my invention is an improved cistern and the method of constructing it are low cost of construction and installation, durability, and resistance to destructive chemical and climatological action. The cistern is designed for the storage of water at fairly even temperatures throughout the year, the water being aerated by the air under pressure, and the water being delivered to the faucet under substantially constant pressures.

Having in view these objects and others which will appear in the description, I will now refer to the drawings, in which

The figure shows a median vertical sectional view of my cistern and of a portion of the well pit.

The structure of my cistern can, at least partly, be best explained by reference to the method of constructing it. I first excavate a relatively deep cylindrical hole in the desired location, the hole having a relatively small diameter. In general the subsoil into which the hole is cut is a stiff, heavy, and tenacious clay which increases in tenacity with increase in depth. I plaster the floor and walls of the excavation with a concrete plaster, in some instances mixing therewith a small proportion of lime plaster. I then build the forms for casting the concrete partition and roof, positioning all of the necessary pipes and connections in the forms before pouring the concrete. The advantages of the plastered walls combined with the cast partition and roof will be fully explained in the subsequent description.

The space enclosed by the walls 10, the floor 11, and the roof 12 is divided by the partition 13 into an upper water chamber and a lower air chamber. This idea of arranging the water chamber above the air chamber is of considerable importance in the solution of the problem of designing a successful concrete pressure cistern, and so far as I am aware the idea is new with me.

The pipe 14 passes through the partition 13 and in water and air tight relation therewith. It may terminate at its lower end either immediately or at some distance beneath the partition, or it may extend almost to the floor 11, but its upper end should be near the roof 12. This pipe 14 serves to

transmit the air pressure to the surface of the water in the water chamber.

Water from the pump is forced through the pipe 15 into the water chamber, and as the water chamber fills up the air in both chambers becomes compressed, the communicating pipe 14 resulting in an equalization of air pressures in the two chambers. The outlet end of the pipe 15, which may be at any level in the water chamber, is provided with an automatic float valve for shutting off the flow of water when the water reaches a predetermined level in the water chamber. This level is preferably immediately beneath the upper end of the pipe 14, as otherwise the water might enter the pipe 14 and be carried down into the air chamber.

The pipe 15 is of course provided with a check valve 16 to prevent the water from flowing back into the well. To avoid damage to the windmill and the connections when the outlet of the pipe 15 is automatically closed by the float valve, I provide a relief valve 17 of any suitable type, and when I so desire I may make use of this relief valve to automatically shut off the windmill. One simple way of doing this is to suspend an empty pail from the shut off lever of the windmill with the mouth of the pail positioned where it will catch the overflow from the relief valve. The weight of the pail and contents will then shut off the windmill. I may however accomplish the same result with any one of a great variety of mechanical or electrical controls. These expedients are so well known however that I do not deem it necessary to illustrate them in the drawings.

When my cistern is properly set up and adjusted, the water from the pump will tend to maintain the requisite air pressure, as there can be no loss of air from the cistern. In the event however that the air pressure should become too low, it is a simple matter to force more air into the cistern through the pipe 15. The water to be used is of course withdrawn through the pipe 18.

Despite all precautions there is a tendency for a certain quantity of water to enter the air chamber, but this quantity will seldom be sufficient to interfere with the operation of my cistern. For removing water which has entered the air chamber, I have provided an outlet pipe 19 with its lower end terminating just above the floor of the air chamber. The pipe 19 passes through the roof of the cistern and terminates in a pit 20, the upper end being provided with a nozzle and a valve. To rid the air chamber of water it is only necessary to open the valve at the upper end of the pipe 19 and to force air through the pipe 15 and into the cistern.

Manholes are provided in the partition and roof respectively. These manholes serve

two purposes. During the construction of the cistern it is necessary that the builder do considerable work on the inside, the manholes being necessary to give the builder access to the interior. Also after the cistern has been in operation for a number of years it may be necessary to enter the cistern for the purpose of repairing or renewing portions of the pipe or for other purposes. The difficulties of providing an air tight and water tight closure for any kind of opening in a concrete wall are very great, and so far as I am aware I am the first to produce an effective closure of that kind and at a cost which will make its installation feasible wherever such a closure is needed.

I will now briefly describe my closure and the method of making it. At the time of casting the partition and roof of my cistern, I embed a rubber ring 21 in the concrete. In some of the cisterns which I have constructed I used the material of which cushion tires for baby carriages, wheeled coasters, and bicycles are made. This I cut into strips of suitable length and united the ends by means of rubber or gutta percha cement, thus making rings which are somewhat larger in diameter than the opening which is to be closed. This ring I secured to the forms in such a way that only a small portion, less than one fourth, would protrude from the lower side of the concrete wall after casting. The closure proper consists of a plate 22 having secured centrally thereto a rod 23 which is screw threaded at its upper end. Above the opening I place a plate 24 or other suitable abutment with the rod 23 passing therethrough, and I then draw the plate 22 tightly against the ring 21 by means of a nut on the screw threaded upper end of the rod 23. This structure may however be varied in several important particulars. Instead of making the ring of rubber, I may employ leather, asphalt, or any other material which is suitable for the purpose. The material must be appreciably compressible, and it should make a fairly close bond with the concrete. This bond should be as nearly air tight as possible, but even in the event that there should be a slight breaking away of the ring from the concrete, the distance around the transverse circumference of the ring is too great to permit the escape of sufficient air to make trouble in the operation of the cistern, and the natural tendency of the compressible material of the ring to fill up small gaps will entirely avoid the occurrence of trouble from this source.

Concrete has been an exceedingly unsatisfactory material for containers for holding air under pressure. Excessive pressures on the walls of such containers are liable to result in hair cracks in the concrete and such hair cracks if permitted to develop in a cistern will entirely destroy the usefulness

of the pressure system because they cause a loss of air pressure through the loss of air, and incidentally they permit the water to seep away through the cracks. Because 5 of the vital importance of this problem in a cistern of the kind which I describe, it is important that the various pressures in the cistern be considered. In the lower or air chamber of my cistern the air pressures are 10 all directed outwardly from the chamber. The pressures on the side walls and floor of the air chamber are practically counterbalanced by the natural resistance of the clay subsoil, and my experience has been that 15 with a favorable subsoil that the plastered wall and floor of the air chamber will develop no hair cracks as the result of internal pressures. The resistance of the soil likewise protects the side walls of the upper 20 or water chamber of my cistern. Air pressures on the top and bottom of the partition 13 are equal, the only inequality in pressures being due to the weight of the water in the upper chamber. This pressure is directed 25 downwardly on the lower portions of the wall 10 but the compression can not develop the strains which result in cracks. The roof 12 is subjected to air pressure on its lower side, but this pressure is only partly coun- 30 terbalanced by the pressure of the weight of the soil above it. The inequality of pressures on the roof results in a tension on the upper portions of the wall 10, and unless provision is made for counteracting the up- 35 ward pressure, cracks will develop in the wall of the water chamber.

I will briefly explain how I protect the side walls of the water chamber against the upward pressure against the roof 12. At the 40 time of casting the partition and roof, I insert reinforcing rods or wires 25. After the setting of the concrete and the removal of the forms I subject the rods or wires to tension and then cover them with concrete 45 plaster in order to protect them from the action of water and air and to prevent their rusting. In some instances I may apply the tension either before or during the setting of the concrete. I may apply the tension to 50 the rods in any one of various ways, as for example by means of nuts and threads on the rods or by drawing together and tying the rods in pairs. The specific details of this feature and the reasons therefor will not be 55 dwelt upon at length in this application, since the structure is the subject matter of my copending application, Serial Number 618733, filed February 12th, 1923.

The dimensions of my cistern are suscep- 60 tible of some variation, but the principles involved in its construction and operation depend very much on dimensions having a small range of variation. The first consider- 65 ation is of course the size, which should be amply large enough to meet the normal

water requirements of the average farm. The present pressure systems will not do this. The cost of the steel tank of ample size is prohibitive. My problem has been the problem of so constructing the pressure cistern of ample size and at a reasonable cost that its installation would be profitable on the great majority of farms. 70

By reducing the diameter and increasing the length of the cistern I very materially 75 reduce the surface of cast concrete and increase the amount of surface of plastered concrete. This results in a very material reduction in costs since it reduces the amount of farm work and since it requires less cement. This latter is readily apparent from the fact that the plastered wall is only about three-fourths of an inch thick while the cast wall is from five to ten inches thick. The reduction of the diameter has another advan- 80 tage in that the danger of cracking the side walls is correspondingly reduced. This is true because the bursting pressure of a cylindrical container of gas under pressure varies directly as the diameter. Still an- 85 other advantage is due to the fact that the upward pressure of the air on the under surface of the roof 12 varies directly as the square of the diameter of the roof. I find it advantageous to construct the roof with a 90 diameter not to exceed five feet three inches. With this diameter and an air pressure of twenty pounds per square inch inside the chamber, the upward pressure on the roof is approximately sixty thousand pounds, and 100 since the weight of the roof is only about eighteen hundred pounds, there must be sufficient reinforcing material to properly anchor the roof to the partition. The reinforcing material is costly, and since there is a 105 considerable reduction in the amount needed with a reduction in the diameter of the cistern, it is obvious that the diameter should be decreased as much as possible, the limit being determined only by the fact that it 110 will be necessary for the operator or builder to do some of the construction work on the inside. If the diameter were reduced to three feet, the upward pressure on the roof would be so small that no reinforcing would 115 be needed.

In a cistern of five feet three inches diameter and having a depth of from seven to seven and a half feet for the water chamber, there will be an ample supply of water for 120 the average farm, with a liberal margin of safety to take care of the requirements for short periods when the wind is not sufficiently strong to pump the water, or when as in the threshing season the drain on the 125 water supply is unusually heavy. In a cistern having these dimensions, I prefer to give the lower or air chamber a depth of from twelve and a half to fourteen feet. The greater the volume of compressed air in 130

the air chamber, the less variation there will be at the faucets. The pressure once established will be maintained by the inflow of water from the pump. No loss of air can occur except that dissolved in the water under pressure, and this quantity will be so small that long periods can elapse before it becomes necessary to restore the air pressure by forcing additional air into the cistern.

10 The cost of construction is of course materially reduced by making both chambers integral and in the same excavation. The equipment for making the excavation is in place and it is simply a continuation of the job to excavate deep enough to provide room for the air and water chambers in a vertical plane. Likewise, the plastering of the walls is simplified by the fact that there is only one continuous wall to be plastered.

20 As before stated, the position of the water chamber above instead of below the air chamber is of vital importance, both in the construction and in the successful operation of my cistern. It is true that if the water were stored in the bottom of the cistern the dividing partition could be dispensed with and that the cost of this partition could thus be saved, but I believe the commercial failures of many of the concrete cisterns here-tofore placed on the market are due to fundamental principles which were overlooked in the designing of such cisterns. In the consideration of concrete as a material for pressure cisterns, the chief factor to be considered is air pressure, because as before stated, internal pressures if excessive are apt to rupture the walls and to produce hair cracks which release the air. In a cistern of the dimensions as I usually employ, a pressure of twenty pounds to the square inch is sufficient to lift the water in the bottom of the water chamber to the required height without causing any undue strain on the walls of the cistern. The thin shell of concrete alone would not resist this pressure. The soil wall however has an ample margin of safety in resisting a pressure of twenty pounds. The concrete wall serves very little more than as an air tight lining for the soil wall. If the water however were stored at the bottom of the cistern, a pressure of about forty-five per cent greater would be required to lift the water at the bottom of the cistern to the same height above the ground. For some soils this pressure is beyond the margin of safety, the only solution of the difficulty being to strengthen the walls at a cost which makes the installation of the concrete cistern entirely out of the question on the great majority of farms. The air pressure is however exerted in all directions with the result that the lifting force against the under side of the roof of the cistern is proportionately increased. This also demands construction which will resist the in-

creased pressure, and whether such construction involves the use of sufficient additional concrete or sufficient additional reinforcing or both, the additional cost must result in the commercial failure of the cistern.

70

While I have described the preferred form of my invention in very specific terms, I do not desire to restrict myself to the exact structure described, since it is obvious that numerous changes could be made without departing from the spirit of my invention. This is especially true of the cistern itself, which I have described as being made of plastered walls and cast top and partition. In some instances it may be desirable to cast the walls also, or even to use other than cementitious materials in the construction of the cistern.

75

80 Having described my invention and its advantages, what I believe to be new and desire to secure by Letters Patent of the United States is:—

85

1. In a cistern, an underground cavity having an air tight lining on its sides and an air tight roof, a substantially horizontal partition dividing the cavity into an upper water chamber and a lower air chamber, means for equalizing the air pressure 90 air chamber and the upper part of the water chamber, and water inlets and outlets for 95 said water chamber, the arrangement being such that water cannot normally enter said lower or air chamber.

95

2. In a cistern, a cavity having an air tight lining on its sides and bottom and having also an air tight roof, a partition dividing the cavity into an upper water chamber and a lower air chamber, means for equalizing the air pressure of said chambers, means for conducting water under pressure into 100 said water chamber, means for automatically stopping the inflow of water when the water reaches a predetermined level in said water chamber, and an outlet for the water whereby the water from the water chamber may 110 be withdrawn.

100

3. In a cistern, an underground cavity, a relatively thin shell of concrete secured to the earth walls and floor of said cavity, a roof for said cavity, a partition dividing the cavity into an upper and a lower chamber, said lower chamber being designed to serve as a container of air under pressure and said upper chamber being designed to serve as a reservoir for the storage of water, means for equalizing the internal pressures of the two chambers, means for conducting water under pressure into said water chamber, and means for withdrawing the water from the bottom of said water chamber, the arrangement being such that water cannot normally enter said lower or air chamber.

115

4. In a cistern, an underground cavity, a relatively thin sheet of concrete secured to the earth walls and to the floor of the cav- 120

125

130

ity, a concrete roof for the cavity, said roof being positioned beneath the surface of the ground, a concrete partition intermediate the floor and roof and dividing said cavity 5 into an upper, water storage reservoir and a lower air pressure chamber, an open pipe terminating in said air pressure chamber and above the water level of said water storage reservoir for equalizing the pressures of the two chambers, means for anchoring the roof to the partition, and means for conducting water into and out of said water chamber.

5. In a cistern, an underground cavity, a

vessel within said cavity, said vessel being 15 enclosed on all sides, a substantially horizontal partition dividing the interior of said vessel into an upper water chamber and a lower air pressure chamber, means for equalizing the internal pressures of said two 20 chambers, means for forcing out water which collects in the bottom of said air pressure chamber, and means for conducting water into and out of said water chamber.

In testimony whereof I affix my signature.

RICHARD E. DILL.
